CASE FOR A SAFETY RAZOR SET

Robert L. Sinclair, Dedham, Mass., assignor to The Gillette Company, Boston, Mass., a corporation of Delaware

Filed Aug. 25, 1959, Ser. No. 57,298

Term of patent 14 years

(Cl. D58—12)

Fig. 1

Fig. 2

Fig. 3

Fig. 4

Fig. 5

Fig. 6

Fig. 1 is a top plan view of a case for a safety razor set, showing my new design;

Fig. 2 is a front elevational view thereof;

Fig. 3 is an elevational view thereof taken from the right side of Fig. 2;

Fig. 4 is a bottom plan view thereof;

Fig. 5 is a rear elevational view thereof; and

Fig. 6 is a perspective view thereof shown in open position.

I claim:

The ornamental design for a case for a safety razor set substantially, as shown.
